UNITED STATES PATENT OFFICE.

LESTER E. HARDING, OF SIOUX CITY, IOWA, ASSIGNOR OF ONE-FOURTH TO EDWARD M. WARD AND ONE-FOURTH TO HENRY HARRIS, OF SIOUX CITY, IOWA.

FARM-TRACTOR.

1,120,477.

Specification of Letters Patent.

Patented Dec. 8, 1914.

Application filed October 1, 1912. Serial No. 723,388.

To all whom it may concern:

Be it known that I, LESTER E. HARDING, a citizen of the United States, residing at Sioux City, in the county of Woodbury and State of Iowa, have invented new and useful Improvements in Farm-Tractors, of which the following is a specification.

This invention relates to farm tractors, and it has for its principal object to produce a convenient and powerful traction engine equipped with an internal combustion motor and which shall be so constructed that it may be readily guided and operated and which shall be furthermore constructed in such a manner that various farm implements may be conveniently connected therewith, or hitched thereto for the purpose of being drawn over the ground.

A further object of the invention is to simplify and improve the frame structure of the machine in such a manner as to enable it to resist any strain to which it is liable to be subjected.

A further object of the invention is to provide simple and efficient means for governing the different working parts of the machine.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings, Figure 1 is a sectional side elevation of a tractor constructed in accordance with the invention. Fig. 2 is a top plan view with parts broken away to show the underlying construction. Fig. 3 is a transverse sectional view, enlarged, taken on the line 3-3 in Fig. 2. Fig. 4 is a longitudinal vertical sectional detail view, enlarged, taken on the line 4-4 in Fig. 2. Fig. 5 is a sectional detail view, enlarged, taken on the line 5-5 in Fig. 2. Fig. 6 is a top plan view of the parts shown in Fig.

5. Fig. 7 is a sectional detail view taken on the line 7-7 in Fig. 6. Fig. 8 is a detail plan view of a portion of the shaft and of the boxing or casting that supports the speed regulating levers. Fig. 9 is a sectional detail view taken on the line 9-9 in Fig. 8. Fig. 10 is a sectional detail view taken on the line 10-10 in Fig. 8. Fig. 11 is a detail side view of one of the link rods. Fig. 12 is a detail plan view of one of the eccentric shafts. Fig. 13 is a sectional detail view taken on the line 13-13 in Fig. 2. Fig. 14 is a detail sectional view of a ball and socket device used on the tractor.

Corresponding parts in the several figures are denoted by like characters of reference.

The main supporting and guiding wheels of the improved tractor are composed each of a cast iron hub 1 which is connected by flat iron spokes 2 with the rims 3-3, said rims being made of T-iron. These rims 3-3 support cross bars or cleats 4 which are likewise made of T-iron and which are riveted or otherwise secured upon the rims 3, thus producing a skeleton construction which is both light and durable and which enables the wheels to hug the ground very closely and effectively, the T-bars or cleats 4 constituting grouts which will bite into the ground, and thus making very effective traction wheels. The hubs of the wheels are support keyed on short shafts 5 which are supported for rotation in bearings 6 and each of which carries at its inner end a spur wheel 7.

The bearings or boxes 6 are associated with and serve to support the frame 8 which is constructed preferably of channel iron or steel and which is reinforced by a yoke 9 likewise formed of channel iron or steel and the limbs or side members of which abut upon and are suitably connected with the boxes or bearings 6 adjacent to the outer ends of the latter, thus serving to greatly strengthen and reinforce the frame structure. The reinforcing yoke 9, which may be regarded as somewhat in the nature of a truss, extends rearwardly from the bearing members 6, and the rearwardly extending portions of the side members of the frame 8 may be regarded as struts co-operating with this truss. Similar yokes or trusses 10 and 11 extend upwardly and downwardly from the bearing members 6 with which the

limbs of said yokes are terminally connected, and struts 10', 11' connect the said yokes or trusses with the bearing members 6 adjacent to the inner ends of the latter. The yokes or trusses 10 and 11 are made of channel iron or steel, and the entire channel frame-work is braced with flat iron braces 12 constituting a rigid frame structure which supports the engine and the gearing.

- 10 The engine and gearing is inclosed within a dust-tight casing 13 of sheet iron or other suitable material, whereby all the working parts are well protected, it being understood that said casing may be provided with doors
15 to afford convenient access to the interior. The casing 13 is supported mainly on the trusses 10 and 11.

The upwardly and downwardly extending truss members 10 and 11 are provided with pivot members 14, 15 with which bracket members 16 and 17 are hingedly connected, said bracket members being extended rearwardly, and said bracket members being also curved in the direction of each other, the upper bracket member 16 being provided with a downward extension 16' and the lower bracket member 17 having an upward extension 17', both of said extensions being bolted or otherwise firmly secured upon a block or bearing member 18 which is firmly supported by the bracket members 16, 17 a suitable distance in rear of the casing 13. The parts are so arranged and proportioned that the casing 13 which is associated with the frame-work of the machine, may turn freely about the axes of the hinge members or pintles 14, 15 with which the bracket members 16, 17 are connected.

40 The block or bearing member 18 is bored longitudinally to form a bearing for a shaft 19 which may be regarded as constituting the tongue of the rear truck, from the frame 20 of which the said shaft extends in a forward direction within the bearing block 18
45 where it is secured against withdrawal by means of one or more keys 21 which, however, will not interfere with the rotation of the shaft within the bearing block. The rear truck is provided with a crank axle 22 having wheels 23 which, owing to the pivotal connection of the truck frame with the bearing block 18 of the main tractor frame, will readily adapt themselves to inequalities in the ground.

55 The motor 24, which may be an internal combustion motor of any approved type, is supported on the main tractor frame, and it serves to drive the main shaft 25 on which friction disks 26 facing one another are securely mounted. The forward end of the shaft 25 projects through the casing of the machine and carries the starting crank 27.

The frame structure of the machine includes brackets 28 rising from the side members of the frame midway between the fric-

tion disks 26, and said brackets support bearing boxes 29, the caps of which 30 are secured by means of bolts 31 having springs 32 whereby said caps are held resiliently in engagement with a transverse shaft 33 70 which is supported for oscillation in the boxes or bearings. The shaft 33, as will be seen by reference to the detail view Fig. 12, is formed with eccentric portions 34, 34 and 35, 35 at opposite sides of its middle portion, 75 Supported on the eccentric portions 34, 35 are pairs of links 36, 37, each of said links having a terminal head or ball 38 seated in a socket 39, said sockets being associated with links 40, 41 which are mounted on eccentric portions of a shaft 33' which is an exact counterpart of the shaft 33, said shaft 33' being supported in bearings 42, the caps of which, 43, are secured by means of bolts 44 having springs 45, whereby said caps are held resiliently in engagement with the shaft 33'. By this manner of mounting the shafts 33 and 33', the said shafts when rocked or oscillated and their respective bearings will be held with some degree of friction which 90 tends to retain said shafts in adjusted position, as will be readily understood. The shafts 33, 33' are provided with cranks, designated, respectively, 46 and 47, whereby they may be rocked in their respective bearings. Each of the links 40 and 41 includes a turn buckle which has been shown in the shape of a right and left threaded rod 48 having a wrench seat 49, whereby it may be turned to regulate the length of the link of 100 which it forms a part.

which it forms a part. The links 36, 36 and 37, 37 support shafts 50, 51 carrying friction wheels 52, 53 which are slidably mounted on the shafts with which they are connected for rotation by 105 keys or splines 54. The friction wheels 52, 53 are of such dimensions that their diameters will almost equal the distance between the faces of the friction disks 26 on the motor driven shaft 25. It will be particularly observed that the eccentric shaft 33 is located almost directly above and approximately in the vertical plane of the axes of the shafts 50 and 51, while the shaft 33' 110 is located in advance of said shafts. It will also be observed, by reference to Fig. 12, 115 that the eccentric portions 34 are diametrically opposite to the eccentric portions 35 of said shafts. When the shaft 33' is rocked in its bearings, it follows that the shafts 50 and 51 carrying the friction wheels 52, 53 will be moved forwardly and rearwardly in 120 opposite directions, placing one of said friction wheels in engagement with the friction disk 26 and the other friction wheel in engagement with the friction disk 26'. It follows that by rocking the shaft 33' so as to 125 reverse the relative positions of the friction wheels 52 and 53, the direction of rotation of said wheels will be reversed, while said 130

wheels 52, 53 being located on diametrically opposite sides of the motor driven shaft which carries the disks 26, 26' will always be rotated in the same direction. This operation may be performed without disturbing the diametrical alinement of the friction wheels 52, 53 with respect to the disks 26, 26'. On the other hand, by rocking the shaft 33 the shafts carrying the wheels 52, 53 may be respectively raised and lowered, and the tendency of their frictional engagement with the faces of the disks 26, 26' will thus be to move them toward or from the axis of the motor driven shaft 25 carrying the disks 26, 26', thereby decreasing or increasing the speed of the wheels 52, 53, as will be readily understood. This arrangement greatly facilitates the operation of the speed regulating mechanism, which will be presently described.

Supported on the shaft 33 about midway between the ends thereof is a box or casting 55 which is shown in detail in Figs. 8, 9 and 10. Said box or casting is bored for the passage of shafts 56 having intermeshing toothed segments 57. Said shafts are also provided with downwardly extending arms or cranks 58, 59 which are slidably connected with the hubs of the friction wheels 52, 53, respectively, so that, by rocking the shafts 56, the wheels 52 and 53 may be moved along the shafts 50 and 51 toward or from each other for the purpose of regulating the speed when the wheels 52, 53 are driven by engagement with the disks 26, 26'. Adjustment of the friction wheels by means of the rock shafts 56 may be effected when the engine is at rest, and the friction wheels are positioned out of engagement with the faces of the friction disks. When the machine is in operation and the friction wheels are in actual frictional contact with the friction disks, the adjustment of the friction wheels will be materially assisted by moving said friction wheels 52, 53 to opposite sides of the diameters of the disks 26, 26' by the means hereinbefore described.

The shafts 50 and 51 are provided with sprockets 59 connected by chains 60 with sprockets 61 on a counter shaft 62 from which motion is transmitted by means of a chain or link belt 63 to a differential gearing on a divided shaft 64, said differential, the casing of which appears at 65, including a sprocket wheel 66 over which the chain 63 is guided. The sections of the divided shaft 64 are provided with pinions 67 meshing into the spur wheels 7 of the axle members 5 which will thus be driven at such speed as may be desired and in the required direction. The shaft 62 carries a band wheel or pulley 68 which, when the machine is utilized as a stationary engine, may be used for transmitting motion to any machinery that is to be driven. When the tractor is thus

utilized it is only necessary to unship a clutch 62' with which the shaft 62 is provided.

A slidably supported plate or frame 69, best seen in Figs. 2, 5, 6 and 7, carries a pair of small friction wheels or pulleys 70, 71 which are located adjacent to opposite sides or faces of a fly wheel 72 on the motor driven shaft 25 so that, by moving the supporting frame or member 69, either one of said wheels may be placed in engagement with the fly wheel, while by placing the supporting member in an intermediate position both of the wheels 70 and 71 may be disengaged from the fly wheel. The shafts 75 of the wheels 70, 71 are provided with pinions or bevel gears 73 meshing with bevel gears 74 on a shaft 75 carrying a worm 76 which meshes into a worm gear 77 on a shaft 78 which is likewise supported for rotation 85 on the frame or member 69. Motion may be transmitted from the shaft 78 by means of a chain 79 to a shaft 80 journaled in a bracket 81 on the frame of the machine, it being evident that the limited sliding movement of the frame or member 69 will not unduly slacken or tighten the chain 79 to interfere with the operation thereof to transmit motion, as required. It is also evident that a chain tightener of any well known type may be employed, if desired, but it has not been considered necessary to show any chain tightening means. It will be readily seen that by shifting the position of the frame or member 69 so as to 95 place either the friction wheel 70 or the wheel 71 in engagement with the fly wheel 72, the direction of rotation of the shaft 80 may be reversed, while by holding the frame or member 69 in an intermediate position, rotation of said shaft 80 may be interrupted. This mechanism is for the purpose of actuating the steering device of the machine which includes an arcuate channel bar 82 which is mounted in the bearing block 18 and which has a rack 83 engaged by the pinion 84 on a shaft 85 which is connected with the shaft 80 by intermeshing bevel gears 86 so as to receive motion therefrom. It will be seen that by rotating the pinion 84, the main carrying frame of the tractor including the casing 13, the axle and the transporting wheels will swing about the axes of the pivot members 14, 15, thereby guiding the machine in the desired direction. It will be seen that the power for steering the machine is thus taken direct from the motor and that, the speed being reduced in transmission, a very desirable and effective steering gear is provided 115 which is considered particularly important and desirable in a farm tractor where short turns are frequently to be made and where the load to be drawn is sometimes quite heavy.

The pivot member 14 on the yoke 10 is bored vertically to accommodate the outermost one of a series of sleeves 87 arranged concentrically within one another and extending from the bracket member 16 through the yoke or brace 10 and within the casing. The sleeves 87 are of different lengths, the innermost one being the longest, and the length being gradually increased so that each sleeve will be provided with ends that project beyond the sleeve wherein it is mounted. Each one of the several sleeves is provided at its upper end with a collar 88 having a radially extending arm 89. Each sleeve is likewise provided at its lower end with a collar 90 having a radially extending arm 91. The arms 91 are connected by links 92 or in any suitable and convenient well known manner with the various parts within the casing that are to be controlled by the operator. Thus, one of said arms is connected with the arm 46 of the rock shaft 33, another with the arm 47 of the rock shaft 33', another with the member 92 whereby the slide 69 of the steering mechanism is operated, and so on. The arms 89 associated with the upwardly extending ends of the sleeves 87 are connected by means of links or connecting rods 93 with hand levers 94 that are fulcrumed on a lever stand 95 which is supported on the bracket member 16 in convenient proximity to the operator whose seat 96 is mounted on spring 97 secured on the bearing block 18 or in some other convenient position on the frame structure. The hand levers 94 are to be provided with stops 98 engaging quadrants 99 of well known construction for the purpose of securing the hand levers and the parts controlled thereby at various adjustments.

Pivotedly mounted on the bracket member 17 are rearwardly extending diverging arms or levers 100, the rear ends of which are connected together by a cross bar 101, see Fig. 13, which constitutes the track on which a carriage 102 is movably supported, said carriage being connected with the ends of a suitably guided chain 103 which is guided over a sprocket wheel 104 on a shaft 105 carrying a hand wheel 106 which is located in a convenient position to be manipulated by the operator, who by turning said wheel may cause the carriage to travel along the cross bar 101 to the point where it shall be desired to apply draft to any agricultural or other implement, such as a gang plow 107 which, for purpose of illustration, has been shown as associated with the machine. The carriage 102 is supported tiltably with reference to the track bar 101, and a lever 108 is provided by means of which the carriage may be tilted so as to adjust the draft vertically. In the drawing the lever 108 which is of the bell

crank type is shown as having one arm connected by means of a link 109 with the beam of the gang plow 107 which may thus be tilted or adjusted; but it is obvious that the link 109 may be connected directly with the carriage 102, or it may be connected with any other implement that in turn is connected with the carriage, the result of the adjustment being the same. A lever 110 has also been shown mounted on the frame of the rear truck for the purpose of effecting vertical adjustment of the rear end of the implement, said lever having an arm 111 which in the present instance has been shown as being connected by a link 112 with the plow for the purpose of raising or lowering the same with reference to the ground. This adjustment may be varied according to the nature of the implement that is being used in connection with the tractor.

From the foregoing description, taken in connection with the drawings hereto annexed, the operation and advantages of this invention will be readily understood by those skilled in the art to which it appertains. The improved tractor is simple in construction, and the structure is of such a nature that it will be found to be extremely durable and wear-resisting. The machine will be found convenient for traction work of any kind, whether in the field or on the road, and it may be conveniently utilized as a stationary engine for the purpose of driving stationary machinery whenever desired without any change whatever in the construction or arrangement of the parts thereof.

Having thus described the invention, what is claimed as new, is:

1. In a farm tractor, a frame structure, upwardly and downwardly extending yokes terminally connected with said frame structure, rearwardly extending brackets pivotally connected with the yoke, said brackets being terminally curved in the direction of each other, and a bearing block supported between the rear ends of the brackets.

2. In a farm tractor, a frame structure, a motor mounted upon the frame, rearwardly extending brackets connected pivotally with the frame, a bearing block supported between the rear ends of the brackets, an arcuate rack supported on the bearing block, a shaft supported for rotation on the frame structure and having a pinion meshing with the rack, and means for transmitting motion from the motor to the pinion carrying shaft.

3. In a farm tractor, a frame structure, rearwardly extending brackets connected pivotally with the frame, a bearing block secured between the rear ends of said brackets, a nest of sleeves extending through the pivot member which connect the upper bracket with the frame, collars connected

with the upper and lower ends of the sleeves and having radially extending arms, controlling levers supported on one of the rearwardly extending brackets, links connecting said levers with the arms extending from the collars at the upper ends of the sleeves and suitable connecting means between the arms extending from the collars at the lower

ends of the sleeve and the parts upon the frame to be actuated. ¹⁰

In testimony whereof I affix my signature in presence of two witnesses.

LESTER E. HARDING.
